(57) **CLAIM**

The ornamental design for an imaging system, substantially as shown and described.

DESCRIPTION

FIG. 1 is a left and front perspective view of an imaging system with an upper display element in a first rotation position, showing my new design;

FIG. 2 is a rear perspective view thereof, with the upper display element in a second rotational position; and,

FIG. 3 is a right and front perspective view thereof, with the upper display element in a third rotational position.

The broken lines in FIGS. 1-3 are included for the purpose of illustrating portions of the imaging system that form no part of the claimed design.
